DESIGN FOR A WALL SWITCH PLATE

David H. Glynn, Richmond Heights, Mo.

Application May 4, 1946, Serial No. 129,312

Term of patent 3½ years

(Cl. D26—13)

To all whom it may concern:

Be it known that I, David H. Glynn, a citizen of the United States, residing at Richmond Heights, in the county of St. Louis and State of Missouri, have invented a new, original, and ornamental Design for a Wall Switch Plate, of which the following is a specification, reference being had to the accompanying drawing, forming part thereof.

In the drawing:

Fig. 1 is a front elevational view of a wall switch plate showing my new design;

Fig. 2 is a rear elevational view thereof;

Fig. 3 is a sectional view taken on the line 3—3 in Fig. 1.

I claim:

The ornamental design for a wall switch plate, substantially as shown.

DAVID H. GLYNN.
